TRANSMITTED POWER MOVER

Oscar A. Henke, Eugene, Oreg.

Application January 22, 1952, Serial No. 267,673

6 Claims. (Cl. 254—29)

1

This invention relates in general to a jacking device, and more specifically to a jacking device in which power is transmitted to pipes or other rod like members for moving same through earth or confined passageways.

The primary object of this invention is to provide an improved device through which power may be transmitted to a pipe or other rod like member for moving same with respect to the device which is anchored.

Another object of this invention is to provide an improved machine which includes a double acting hydraulic piston whereby pipe or other rod like members may be either pulled or pushed by the machine due to pressure transmitted thereto.

Another object of this invention is to provide an improved machine which includes a base having means attached thereto for conveniently anchoring the base to the ground or other stationary objects.

Another object of this invention is to provide an improved machine for transmitting power to pipes for moving same, said machine including a carriage slideable with respect to the base of the machine.

Another object of this invention is to provide a sliding carriage of generally channel shaped cross section, said carriage having mounted therein a fixed pipe gripping block and pivotal pipe gripping clamps, said pipe gripping clamps being adapted to cooperate with the pipe gripping block to tightly engage a pipe or other rod like members therebetween.

Another object of this invention is to provide an improved machine for transmitting power to a pipe, said machine including a base having a transverse rod at each end for selectively mounting a hydraulic piston thereon, said rod intersecting a ground engaging stake receiving sleeve carried by said base, and said rod being retained in said base by said ground engaging stake.

Another object of this invention is to provide an improved machine for transmitting power to a pipe for moving same, said machine being of compact and simple construction whereby it may be usually moved and economically manufactured.

A further object of this invention is to provide an improved machine for transmitting power to a pipe for moving same, said machine including a base, a carriage slideable in said base and a double acting hydraulic piston carried by said base for sliding said carriage with respect to

2

said base, whereby a pipe may be either pushed or pulled with respect to said machine.

With these objects definitely in view, this invention resides in certain novel features of construction, combination and arrangement of elements and portions as will be hereinafter described in detail, in the specification, particularly pointed out in the appended claims, and illustrated in the accompanying drawings which form a material part of this application, and in which:

Figure 1 is a side elevational view of the machine for transmitting power to a pipe, said machine being the subject of this invention, and showing same secured to the ground and in engagement with a pipe;

Figure 2 is a top plan view of the machine of Figure 1 and showing the arrangement of the base, the carriage and a hydraulic piston carried by said base for moving said carriage with respect to said base, said base, carriage and hydraulic piston being elements of the machine;

Figure 3 is a transverse horizontal sectional view taken substantially upon the plane indicated by the section line 3—3 of Figure 4 and showing the construction of the pipe gripping means, a pipe being illustrated as being gripped by said means for pushing same; and

Figure 4 is an enlarged end elevational view of the machine of Figure 1 as viewed from the left and showing the arrangement of the various elements of the machine.

Similar characters of reference designate similar or identical elements and portions throughout the specification and throughout the different views of the drawings.

Referring now to the drawings in detail, the machine which is the subject of this invention includes a base referred to generally by the reference numeral 10. The base 10 includes a pair of spaced parallel side members 12 each having base flange 14, a narrow longitudinal side wall portion 16 normal to the base flange 14, and an inwardly sloping upper side wall portion 18. Extending inwardly from the upper inwardly sloping side wall portion 18 is a flange 20 in spaced parallel relation to the base flange 14. The base flange 14 and the flange 20 in combination with the side wall portions 16 and 18 form a guideway 22.

As is best shown in Figure 1, the inwardly extending upper side wall portion 18 is provided with a concave upper edge 24 and outwardly and downwardly sloping end edges 26. Rigidly secured to each side wall portion 18 adjacent

its end edges 26 are downwardly and outwardly sloping tubular sleeve members 28 whose bottoms are coplanar with the bottom surface of the base flange 14. Removably carried by each of the tubular sleeve members 28 is a ground engaging stake 30 having a head 32 and a pointed end 34.

The spaced side portions 12 of the base 10 are secured together in spaced parallel relation by transverse frame members 36 extending between the side wall portions 18 and secured thereto adjacent their end edges 26. The transverse frame members 36 are also secured to the upper surface of the flanges 20 adjacent their ends. The lower edge of the transverse frame member 36 between the flanges 20 is concaved upwardly.

Slidably mounted within the guideways 22 of the sides 12 is a generally channel shaped carriage 38 having a top horizontal plate portion 40, side flanges 42, and inturned wing flanges 44 at the lower edges of the side edges 42. A top plate portion 40 engaging beneath the flanges 20 and the inturned wing flanges 44 overlying the base flanges 14.

Referring now to Figure 3 in particular, it will be seen that the carriage 38 only extends a portion of the length of the base 10 and is provided at one side in the interior thereof with an elongated pipe gripping block 46 which is secured to the flanges 42 and 44 at one side of the carriage in spaced relation to the upper plate 40. The inner edge of the pipe gripping block 46 is provided with a longitudinally extending triangular groove 48 for receiving a portion of a longitudinally extending pipe therein.

Carried at the other side of the carriage 38 are a pair of spaced pipe gripping clamps 50 and 52. The pipe gripping clamps 50 and 52 are provided with handle portions 54 and 56, respectively, extending therethrough and journaled in the wing flange 44 and the upper plate 40 of one side of the carriage 38. As is best illustrated in Figure 4, mounted on the handles 54 and 56 between the upper surface of the pipe gripping clamps 50 and 52, respectively, and the plate portion 40 are compression springs 58. The compression springs 58 tend to cause binding of the pipe gripping clamps 50 and 52 so that they are maintained in any position to which they are turned by the handles 54 and 56, respectively. The handles 54 and 56 are provided with an offset crank portion at their upper ends in order to facilitate rotation of the handles and their associated pipe gripping clamps.

Referring now to Figure 3, it will be seen that the pipe gripping clamps 50 and 52 are each generally rectangular in plan view and each having a rounded side opposite its respective handle. The rounded side of each the pipe gripping clamps 50 and 52 is provided with a triangular notch similar to the triangular notch in the edge 48 of the pipe gripping block 46.

It will be noted that the rounded side of the pipe gripping clamp 50 is illustrated as being in engagement with the surface of a pipe 60 and clamping same against the edge 48 of the pipe gripping block 46. Any attempt of the pipe 60 to move to the left, as viewed in Figure 3, will result in clockwise rotation of the pipe gripping clamp 50 about its handle 54, and thereby more tightly grip the pipe 60.

If it is desired to move the pipe 60 to the left, as illustrated in Figure 3, the pipe gripping clamp 50 is released from engagement with the pipe 60 by turning its handle 54, and the pipe gripping

clamp 52 is turned into engagement with the pipe 60. It will be noted that the shape of the pipe gripping clamp 52 is just the opposite of that of the pipe gripping clamp 50 so that when the rounded side of the pipe gripping clamp 52 engages the pipe 60, movement of the pipe 60 to the right, as viewed in Figure 3, will result in counter-clockwise rotation of the pipe gripping clamp 52 to tightly clamp the pipe 60 against the pipe gripping block 46.

Referring now to Figure 2 in particular, it will be seen that secured to the inner side of the upper side wall portions 18 in transverse alignment with the tubular sleeve members 28 are pairs of aligned tubular support members 62. The tubular support members of each pair are in alignment with each other with their free ends spaced slightly from each other in opposed relation. The tubular support members 62 are additionally supported by being welded to the upper edge of their associated transverse frame member 36.

Carried within each pair of tubular frame members 62 is a rod 64. In order that the rod 64 may be inserted within and removed from the tubular support member 62, one side wall portion 18 and its associated tubular sleeve members 28 are provided with aligned apertures in alignment with the associated tubular support members 62. The aperture in the outer portion of the tubular sleeve members 28 being clearly shown in Figure 2 and referred to by reference numeral 66. It will be noted that the rods 64 can be removed from within the tubular support member 62 only by first removing the ground engaging stake 30 inserted within its associated tubular sleeve member 28 having the aligned aperture 66 therein.

Pivoted secured on one of the rods 64 between the opposed ends of the tubular support members 62 is a hydraulic piston 68 having a cylinder 70 and a connecting rod 72. The cylinder 70 has on its rear end a connecting block 74 which is mounted on the rod 64. The free end of the connector rod 72 is pivotally connected between a pair of spaced parallel ears 76 secured to the upper side of the plate portion 40 of the carriage 38. The connection between the connector rod 72 and the ears 76 is a pivotal connection due to the connection of the elements by a pivot pin 78.

Carried by the cylinder 70 is a pair of hydraulic hoses 80 and 82 which are connected to a hydraulic motor and a reservoir through a four way valve (not shown). The hydraulic piston 68 being a double acting piston, it is readily apparent that the connecting rod 72 may be reciprocated by selectively positioning the four way valve.

While the hydraulic piston 68 is illustrated as being connected to the rod 64 at the left side of the machine as viewed in Figure 2, it may equally well be secured to the rod 64 at the right side of the machine. Due to the fact that the hydraulic piston 68 may be connected to either end of the base 10, it is obvious that the pipe gripping clamps 50 and 52 may be utilized to both push and pull pipe 60 depending upon the position of the hydraulic piston 68.

While this machine has been illustrated and described as being secured to the ground for the purpose of moving a pipe 60 therethrough and pushing same into dirt, it is not intended to so limit the invention; the machine is capable of moving other rod like members through dirt, either by pulling or pushing, or it may be utilized to pull pipe from wells. Furthermore, it may be utilized for pulling cables through conduits or other similar uses.

The operation of this machine will be readily understood from the foregoing description of the mechanical details thereof, taken in connection with the above recited objects and drawings. Further description would appear to be unnecessary.

Minor modification of the machine, varying in minor details from the embodiment of the machine illustrated and described here, may be resorted to without departure from the spirit and the scope of this invention, as defined in the appended claims.

Having described the invention, what is claimed as new is:

1. A transmitted power mover comprising a base having longitudinally extending guideways therein, a carriage slidably mounted in said guideways, pipe gripping means carried by said carriage, means carried by said base for sliding said carriage in said guideways, said means for sliding said carriage being a hydraulic piston, said base having shaped side walls, aligned tubular support members extending inwardly therefrom, a rod carried by said aligned tubular support members, one end of said hydraulic piston being pivotally mounted on said rod between the ends of said tubular support members.

2. A transmitted power mover comprising a base having longitudinally extending guideways therein, a carriage slidably mounted in said guideways, pipe gripping means carried by said carriage, means carried by said base for sliding said carriage in said guideways, said means for sliding said carriage being a hydraulic piston, said base having shaped side walls, aligned tubular support members extending inwardly therefrom, a rod carried by said aligned tubular support members, one end of said hydraulic piston being pivotally mounted on said rod between the ends of said tubular support members, said base having a plurality of tubular sleeve members carried by side walls thereof, said sleeve members being provided with ground engageable stakes for anchoring said base to the ground.

3. The combination of claim 2 wherein the axes of the tubular sleeve members intersect the axes of said rod and said tubular support members, said rod passing through one of said tubular sleeve members when being inserted and removed from said tubular support members, said rod being retained in position by one of said stakes.

4. In a transmitted power mover, a base comprising a pair of spaced parallel side members including upwardly and inwardly sloping side walls, transverse end members extending between upper portions of said side walls and connecting said side members together, means for securing said base to a supporting surface, said side members including opposed longitudinally

extending guideways, said means including aligned pairs of tubular sleeve members secured to outer faces of said side walls for receiving anchoring stakes, transversely aligned pairs of tubular support members carried by inner faces of said side walls, axes of said tubular support members intersecting axes of adjacent tubular sleeve members, rods positioned in said tubular support members, aligned bores in one of said side walls and its associated tubular sleeve members to facilitate positioning of said rods in said tubular support members, said rods being adapted to be retained in place by anchoring stakes received in said tubular sleeve members 15 having said bores formed therein.

5. The base of claim 4, wherein said tubular support members have spaced opposed ends to facilitate the mounting of force exerting means on rods passing therethrough.

6. In a transmitted power mover, a base comprising a pair of spaced parallel side members including upwardly and inwardly sloping side walls, transverse end members extending between upper portions of said side walls and connecting said side members together, means for securing said base to a supporting surface, said side members including aligned pairs of tubular sleeve members secured to outer faces of said side walls for receiving anchoring stakes, transversely aligned pairs of tubular support members carried by inner faces of said side walls, rods positioned in said tubular supports, axes of said tubular support members intersecting axes of adjacent tubular sleeve members, aligned bores in one of said side walls and its associated tubular sleeve members to facilitate positioning of said rods in said tubular support members, said rods being adapted to be retained in place by anchoring stakes received in said tubular sleeve members having said bores formed therein, a carriage slidably mounted in said guideways, force exerting means connecting the carriage to the base, said carriage being of an inverted channel shaped cross section and including inturned flanges, shafts extending between one of said flanges and a web of said carriage, pipe gripping clamps mounted on said shafts for pivotal movement, a fixed pipe gripping block disposed between the other of said flanges and said web for cooperation with said pipe gripping clamps.
